CLAIM

The ornamental design for a core for rotary electric machine, as shown and described.

DESCRIPTION

FIG. 1 is a perspective view of a first embodiment of a core for rotary electric machine showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a cross-sectional view thereof taken along the line 8-8 in FIG. 6;

FIG. 9 is a cross-sectional view thereof taken along the line 9-9 in FIG. 6;

FIG. 10 is a perspective view of the core for rotary electric machine in a condition of use.

FIG. 11 is a perspective view of a second embodiment of a core for rotary electric machine showing our new design;

FIG. 12 is a front view thereof;

FIG. 13 is a rear view thereof;

FIG. 14 is a left side view thereof;

FIG. 15 is a right side view thereof;

FIG. 16 is a top view thereof;

FIG. 17 is a bottom view thereof;

FIG. 18 is a cross-sectional view thereof taken along the line 18-18 in FIG. 16;

FIG. 19 is a cross-sectional view thereof taken along the line 19-19 in FIG. 16; and,

FIG. 20 is a perspective view of the core for rotary electric machine in a condition of use.

The broken lines in the figures are included for the purpose of illustrating the unclaimed portions of the core for rotary
